HANDLE FOR STOVE DOORS

William D. Watt, Grand Rapids, Mich., assignor to
Keeler Brass Company, Grand Rapids, Mich.

Filed Jan. 11, 1960, Ser. No. 59,008

Term of patent 14 years

(Cl. D81—25)

Fig. 1 is a plan view of a handle for stove doors embodying my new design.

Fig. 2 is a front elevational view; and

Fig. 3 is an end elevational view.

My design for a handle for stove doors is characterized by the particular combined bracket and end elements, in association with the elongated cylindrical center element which tapers from the center outward, all as shown.

I claim:

The ornamental design for a handle for stove doors, as shown and described.
